JOSEPH PERCY REMINGTON, OF PHILADELPHIA, PENNSYLVANIA, ASSIGNOR TO
REMINGTON MANUFACTURING COMPANY, OF PHILADELPHIA, PENNSYLVANIA, A CORPORATION OF PENNSYLVANIA.

MEANS FOR SUPPLYING LIQUID FUEL TO EXPLOSIVE-MOTORS.

1,373,912.

Specification of Letters Patent.

Patented Apr. 5, 1921.

Application filed May 26, 1919. Serial No. 299,837.

To all whom it may concern:

Be it known that I, JOSEPH P. REMINGTON, a citizen of the United States, and resident of Philadelphia, county of Philadelphia, and State of Pennsylvania, have invented an Improvement in Means for Supplying Liquid Fuel to Explosive-Motors, of which the following is a specification.

My invention has for its object the provision of suitable means for supplying gasoline or other explosive fluid to a motor from a source of supply which is located at a lower level than that of the carbureter of the motor, and which means shall be simple in construction, positive in action, inexpensive to manufacture and requiring very little space for installation.

A further object of my invention is to provide a system for raising the gasoline or other fluid to an elevation sufficient to insure the flow, by gravity, to the carbureter in such a manner that the flow shall be practically continuous during the operation of the motor, so as to avoid the necessity of large reservoirs or tanks for directly supplying the carbureter with the fluid; this being accomplished by providing a direct pumping operation as distinguished from a continuous suction and with the result that approximately only sufficient gasoline is drawn to the higher level of the motor as would be required by the said motor under its maximum consumption. The pumping action is secured by providing the suction from a single cylinder of the motor, so as to obtain positive intermittent action as distinguished from a practically continuous suction which would be secured from the intake manifold of a multiple cylinder motor. While in my improved system it is intended that the supply of gasoline shall be maintained approximately in accordance with the consumption, it is manifest that the rate of consumption with the same engine varies under different speeds and loads and consequently provision is made for operation between maximum and minimum requirements, and the devices are so constructed that this condition is maintained by control of the liquid supply, to prevent, on the one hand, an abnormal rise of the liquid in the system and, on the other hand, an abnormal return of the liquid to the storage

tank during any variation in the operation of the motor.

With the above and other objects in view, the nature of which will be more fully understood from the description taken in connection with the drawings, the invention consists in the novel construction of apparatus as hereinafter more fully described and defined in the claims.

Referring to the drawings: Figure 1 is a diagrammatic elevation, illustrating the application of my invention to a motor and supply tank; Fig. 2 is a vertical sectional view of the means for controlling the flow of the gasoline; Fig. 3 is a vertical section taken on the line 3—3 of Fig. 2, but on a larger scale; and Fig. 4 is a perspective view of the valve piece shown in Figs. 2 and 3, which is directly operated by the intermittent pressure of the motor cylinder.

2 illustrates a multiple cylinder motor of any suitable character, such as employed in automobiles or motor boats, and in which the several cylinders 3 may be supplied from a common carbureter 4, through the usual manifold system. 5 is the reservoir or supply tank and which is shown at a lower level than the carbureter 4, and from which the gasoline or other explosive fluid is required to flow through pipes 7 and 8 to the carbureter under the regulation of the control mechanism 6 which is arranged at a higher elevation than the carbureter and made effective by the varying pressure, due to the pulsations supplied through a pipe 9 from one of the plurality of cylinders 3.

In the operation of this apparatus, the single cylinder 3 operates as a pump to supply suction and pressure alternately through the pipe 9, these actions of suction and pressure taking place alternately in a rapid intermittent manner during the running of the motor. The construction of the device 6 is such that the suction impulses produced in the pipe 9 are intermittently made effective to create vacuum impulses within the chamber of the said device, whereas the pressure impulses in the pipe 9 are excluded as far as possible from the said chamber of the device. In this manner, the gasoline is caused to flow from the tank 5 upwardly through the pipe 7 and into the chamber of the device 6, and thence, by gravity, to pass through

pipe 8 to the carbureter 4. The device 6 is provided with valve means to prevent a back flow of the gasoline to the tank 5 except at certain times and at the same time is provided with means for permitting access of atmospheric pressure to its chamber alternately with the suction impulses, these suction impulses and atmospheric admissions being produced in rapid succession during the normal running of the motor.

More specifically describing the internal construction of the control device 6, reference will be made to Figs. 2, 3 and 4, which illustrate a preferred construction. 10 is a tubular body which is closed at top and bottom to provide a float chamber. At the bottom, this body 10 is screwed into a base 11 provided with an outlet 12 for connection with the pipe 8 which leads to the carbureter 4; and this outlet 12 is provided with a check valve 13 which permits free flow of gasoline from the float chamber to the carbureter, but prevents any suction within the float chamber drawing the gasoline from the carbureter through the pipe 8 into the float chamber. Screwed into the bottom of the base 11 is a bushing 14 having a screw threaded nipple for connection with the supply pipe 7 leading from the reservoir 5. The bushing 14 is recessed on its upper part to provide an enlarged chamber 15, and when screwed into place within the bottom of the base 11, it is made to clamp a strainer 16 of suitable material in position to prevent any particles of dirt finding its way from the reservoir 5 to the float chamber and thence to the carbureter. The base piece 11, immediately above the strainer 16 is provided with a vertical aperture 17 opening into the float chamber within the tubular body 10. The lower portion of this aperture is provided with a valve seat 32 upon which seats a check valve 30 to permit flow of gasoline from the reservoir 5 and pipe 7 into the float chamber of the body 10, but prevent backflow from said chamber. The upper part of the passage 17 is provided with an annular bushing 17^a which retains the check valve 30 within its valve chamber (formed by the passage 17 between the bushing and valve seat) and also acts as a guide for the lower end of the float to be later described.

The top of the tubular body 10 is screwed tightly into a head 18 which is provided with a vertical passage 23 and a horizontal passage 20, said passages communicating with each other, as shown. The horizontal passage 20 is provided at one end with a valve seat 21 and at the other end with a valve seat 22, said valve seats facing in opposite directions. The passage 20 and its valve seat 21 are in communication with a threaded nipple 19 with which the pipe 9 (Fig. 1) is connected. 25 is a valve stem

preferably square in cross section (Fig. 3) and has upon one end a valve piece 26 and on the other end a valve piece 27, said valve pieces respectively adapted to coöperate with the seats 21 and 22 aforesaid. The length 70 of the valve stem 25 is such that the valve pieces 26 and 27 are separated a slightly greater distance than are the seats 21 and 22, so that when the valve piece 26 seats tightly upon the seat 21, the valve piece 27 is clear 75 of its seat 22, as illustrated in Fig. 2. Similarly, when the valve piece 27 is seated tightly upon its seat 22, the valve piece 26 will be off its seat 21. This valve piece is put into rapid reciprocation during the normal running of the motor, as it makes one reciprocation with each reciprocation of the piston in the cylinder with which it is in communication through the pipe 9.

A float 28 is arranged within the float 85 chamber formed by the tubular body 10 and this float is of elongated shape in a vertical direction, so that the diameter of the body 10 is relatively small. The upper end of the float 28 is provided with a conical valve 90 piece 29, the extension of which is guided in the aperture 23. The lower edge of this aperture constitutes a valve seat 24 in which the conical valve piece 29 seats when the float is sufficiently raised by the presence of 95 gasoline in the float chamber, as indicated in Fig. 2. When this condition takes place, the suction produced by the motor does not become effective upon the contents of the float chamber because the valve piece 29 acts 100 as a check valve to close the communication with the float chamber. The lower end of the float 28 is provided with a guide pin 31 which is received in and guided by the annular bushing 17^a aforesaid, so that the float 105 is guided vertically without contacting with the sides of the body 10.

The operation will now be understood:— Assuming that the motor is in operation with the preliminary supply of gasoline in 110 the carbureter, the alternate suction and pressure which is produced in the cylinder 3 connecting with the pipe 9, will exert alternately a suction and pressure through said pipe in synchronism with the reciprocations 115 of the piston in the motor, and this will be with every reciprocation of the piston, whether the motor be a two-cycle or four-cycle machine. The higher the speed of the motor, the more rapid will be the alternations between suction and pressure in the pipe 9. The effect of the alternating suction and pressure in the pipe 9 is to reciprocate the valve piece 25. On the suction stroke of the motor, the valve piece 25 is 120 moved to the right (Fig. 2) and this enables the suction to extend into the float chamber, causing inflow of gasoline until the float 28 is lifted sufficiently to close the aperture 23. The suction impulses will cause the gasoline 130

to flow from the reservoir 5 through pipe 7 and upwardly into the float chamber, and in this case the gasoline will pass from the chamber 15 through the strainer 16 and 5 passage 17 into the float chamber. During the normal operation of the device, the check valve 30 prevents backflow of gasoline from the float chamber to the reservoir and consequently the gasoline is retained except as 10 it may be fed to the carbureter.

On the pressure stroke of the motor, the valve piece 25 is moved to the left, to the position shown in Fig. 2, in which case the pressure is shut off from the float chamber 15 and at the same time said float chamber is in communication with the atmosphere by reason of the fact that the valve piece 27 is moved away from its seat 22. When this 15 action takes place, the gasoline within the 20 float chamber is free to pass by the check valve 13 and through pipe 8 to the carbureter 4, it being understood that the float controlling valve of the carbureter regulates the delivery of gasoline to the carbureter in 25 accordance with its requirements. If during the normal operation of the apparatus, the gasoline in the float chamber rises to the level indicated in Fig. 2, it will raise 30 the float and, in so doing, cause the valve piece 29 to seat at 24 to close the passage 23, so that no further suction can exert its influence within the float chamber to increase the height of the gasoline therein; and this 35 condition will be maintained until the level of the gasoline in the float chamber descends sufficiently to lower the float, by the gasoline passing to the carbureter. Under normal 40 operation of the motor, the gasoline sucked into the float chamber would be slightly in excess of requirements to insure a sufficiency of supply; but irrespective of the speeds of the motor, the suction is automatically shut off from the float chamber by the valve piece 29 in case of an excess of 45 gasoline in the float chamber. Should the motor continue to operate at high speed and thereby provide suction upon the float chamber in excess of what is normally necessary, then in such case, the gasoline will rise to 50 a level sufficient to lift the float and its valve piece 29 to shut off the suction by sealing the passage 23, and maintaining this condition until the level of the gasoline lowers sufficiently. The valve piece 29 acts as a 55 check against abnormal rise of the gasoline and loss by drawing it out of the float chamber. By means of the devices above referred to, the level of the gasoline is maintained within reasonably close levels, which 60 insure an average normal static head sufficient to insure proper supplying of gasoline to the carbureter under all possible conditions.

I have shown a vent aperture 36 (Fig. 2) 65 opening from the float chamber into the

valve seat 22 which, when the valve piece 27 is off its seat, will permit ready access of air into the float chamber to break any vacuum that might be therein and to insure the flow of the gasoline to the carbureter. The vent 70 aperture 36 positively admits air to the float chamber in an intermittent manner and is especially relied upon when the float is raised sufficiently high to have its valve piece 29 seal the air passages 23. If it were 75 not for the vent aperture 36, controlled by the valve piece 27, it is manifest that when the fluid level in the float chamber reached a maximum, as indicated in Fig. 2, the gasoline would not flow properly to the carbureter, since there would be no way of lowering 80 the float and its valve piece 29 to permit inflow of air.

The alternate action of the suction and pressure upon the valve pieces 26 and 27, is 85 to make them reciprocate rapidly and to produce in the float chamber corresponding suction and pressure effects, the former drawing the gasoline from the reservoir 5 into the float chamber, and the latter caus- 90 ing it to flow to the carbureter; and these results are so rapidly alternated, that the flow from the reservoir 5 to the carbureter 4 may be taken as a practically continuous action commensurate with the motor re- 95 quirements. Because of this, it is not necessary to provide large vacuum tanks which are alternately subjected to vacuum and atmospheric pressure at long intervals under the control of a float actuated valve mechanism, as has heretofore been the customary practice; but instead, my improved system permits of the use of a chamber between the reservoir and carbureter of minimum size, 100 as above pointed out. 105

By reference to Figs. 3 and 4, it will be seen that the stem 25 of the valve pieces 26 and 27 is made square in cross section and the purpose of this is that it shall touch the aperture 20 at four places, so that it is properly guided thereby while permitting the 110 passage of air and thereby obviates the necessity of additional guiding means.

Apparatus of this character requires very little additional space under the engine hood of an automobile, because the control devices 115 6 are only approximately six inches long by one inch in diameter and, therefore, it has been found exceedingly easy to install apparatus of this character in the available 120 space in automobiles.

I have described my improved method and means in that particularity which I deem to be the best exposition of my invention, and that which I prefer in commercial 125 practice, but I do not restrict or confine myself to the minor or secondary details, as such variations may be resorted to as matters of mechanical skill and without a departure from the spirit of the invention. 130

Having now described my invention, what I claim as new and desire to secure by Letters Patents is:—

1. Means for supplying liquid fuel to an explosive motor, comprising the combination of a motor provided with a carbureter, and a reservoir for liquid fuel at a lower elevation than the carbureter, combined with a chamber at a higher elevation than the carbureter, a pipe leading from the lower part of the chamber to the carbureter for supplying liquid fuel thereto, a pipe leading from the reservoir to the lower part of the chamber, a freely operating gravity actuated check valve interposed between the chamber and reservoir to permit flow of liquid fuel from the reservoir into the chamber and prevent backflow therefrom, a pipe leading from the upper part of the chamber and connecting with a cylinder of the motor whereby rapid alternating impulses of suction and pressure are exerted in said pipe during the normal operation of the motor, and a valve device for providing rapid alternating communication between the upper part of the chamber and the atmosphere on one hand and the pipe connecting with the motor cylinder during its suction cycle on the other hand, said valve device arranged for synchronous reciprocation with each change from pressure to suction and vice versa, in the cylinder of the motor.
2. The construction specified in claim 1, having the chamber provided with a vertically movable float furnished at its upper end with a valve piece for opening and closing communication between the chamber and the valve device which controls the communication with the pipe connecting with the cylinder of the motor, whereby when the liquid fuel has risen in the chamber to a maximum level, further suction from the cylinder of the motor will be ineffective upon the contents of the chamber until the level of the liquid fuel therein has become sufficiently lowered.

3. The invention specified in claim 1, having the chamber provided with a vertically movable float actuated valve for automatically closing communication between the chamber and the valve device which controls communication with the pipe connecting with the cylinder of the motor and operating when the liquid fuel has risen in the chamber to a maximum level, and a vent aperture opening from the chamber and controlled by the valve piece of the valve de-

vice for providing communication between the chamber and the atmosphere.

4. The invention specified in claim 1, having the device for providing communication between the cylinder of the motor and the interior of the chamber formed as a check valve closing toward the chamber under pressure impulses of the motor, and having further an additional check valve movable under the action of the varying liquid level within the chamber, whereby the suction produced by the motor is not permitted to affect the liquid within the chamber after it reaches a maximum level.

5. The invention specified in claim 1, further having the chamber provided with a float and valve piece to close communication with the upper part of the chamber when a maximum level of liquid fuel is contained therein, whereby a normally closed or normally open communication may be automatically provided with the chamber according to the level of the liquid fuel therein and without interfering with the normal rapid reciprocations of the valve device which is affected by the alternating pressure and suction effects produced within the motor.

6. In a device for controlling the supply of liquid fuel to a motor, the combination of a float chamber having at the bottom an intake port and a discharge port, freely acting check valves for respectively permitting the inflow of fluid to the float chamber and outflow of fluid from the float chamber through the discharge port, a passage from the upper part of the float chamber having communication both with the atmosphere and with an inlet port arranged for communication with a source of alternating suction and pressure, two check valves connected together and movable as a unit for alternately shutting off communication between the chamber and the atmosphere while opening communication between the chamber and the inlet port leading to the source of suction and pressure and vice versa, and a float operated valve within the float chamber for controlling communication between the upper part thereof and the inlet port leading to the source of suction and pressure whereby the latter may be shut off automatically whenever the liquid within the chamber rises to a maximum level.

In testimony of which invention, I hereunto set my hand.

JOSEPH PERCY REMINGTON.
